CALCULATING MACHINE

Robert L. Muller, Detroit, Mich., assignor to Burroughs Adding Machine Company, Detroit, Mich., a corporation of Michigan

Application November 20, 1933, Serial No. 698,768

7 Claims. (Cl. 235—60)

This invention relates to a calculating machine and it is concerned particularly with a feature that is sometimes referred to as "enforced designation".

It is desirable, in some uses of calculating machines, to require the manipulation of a certain key or member before the machine can be operated, or before some part of it can be released. Generally speaking, the manipulation of this particular member results in printing a special character which indicates or records, or "designates" that the member has been manipulated. But it is not always necessary to print a character in connection with the enforced manner of operating the machine and the term "enforced designation" as used herein, is not intended to be limited to the enforced printing of a character but is simply a convenient term used to refer to a construction which requires a certain enforced manner of operating a machine, no matter whether a special character is printed or not.

Machines have been heretofore constructed having enforced designation mechanisms, but these mechanisms are generally built into the machines at the factory. The machine, as it arrived in the customer's hands, is constructed to operate, as far as the enforced designation feature is concerned, in a definite way. Sometimes these features can be changed by the substitution of proper parts but, as far as the customer is concerned, his machine operates in a definite way until it is altered.

While the customer may want an enforced designation feature in certain operations of his machine, he often does not want this feature for certain other operations. This is particularly true in large bookkeeping or statistical machines where a series of operations are performed in sequence.

The present invention is directed to a solution of this problem and it comprehends a provision of automatic means for rendering the enforced designation feature active when it is wanted and inactive when it is not wanted.

The general object of the invention is to provide an improved automatically controlled enforced designation mechanism for a calculating machine.

Other and more particular objects of the invention will hereinafter appear.

An embodiment of the invention is shown in the accompanying drawings in which:

Figure 1 is a right side elevation of a machine with the invention applied to it, and with the designation keys shown in an intermediate bank

of keys, the parts being shown in normal position;

Fig. 2 is a view similar to Fig. 1, showing the position of the parts after a designation key has been depressed and with the mechanism in position to enable the machine to be operated;

Fig. 3 is another view similar to Fig. 1 with the enforced designation feature disabled under the control of the paper carriage;

Fig. 4 is a view similar to Fig. 1 showing a modified form of the invention in which a plurality of columns of designation keys control the operation of the machine;

Fig. 5 is a detail elevation of a portion of the front of the machine shown in Fig. 6;

Fig. 6 is a view similar to Fig. 4 with the enforced designation feature conditioned for operation by the paper carriage; and

Fig. 7 is a view similar to Fig. 6 showing the position of the parts after a designation key has been depressed.

The invention is shown applied to a Burroughs high keyboard machine, the general features of which are well known, but some of which will be briefly described in order that the present invention may be clearly understood.

General machine features

The machine is provided with a plurality of amount keys 10 (Fig. 1) which control the differential positioning of the actuator racks 11. The actuator racks are carried by arms 12 pivoted at 13 and these arms carry, on their rear ends, a series of movable types 14. After the actuator racks 11 and the arms 12 are differentially positioned, a printing mechanism including hammers 15 operates to drive the types to printing position against a platen P carried by a traveling paper carriage C. The paper carriage comprises a paper supporting means and, in order to provide for printing in different columns on the paper, a column printing control means is provided in the form of a tabulating mechanism 16 that controls the movements of the carriage from column to column across the machine.

Cooperating with the actuator racks 11 is a register 17 which adds, subtracts, yields totals, etc., and a set of multiple registers 18 of the type shown in Patent No. 1,909,715.

While the enforced designation mechanism might be applied to different parts of the machine it is, in embodiment of the invention illustrated herein, applied to the control of the motor drive which calls for a brief review of the construction of the motor drive.

The machine is driven by an electric motor 20 through a clutch 21. This clutch is thrown into operation and the motor caused to give the machine a stroke of operation by means of a vertically movable motor control link 22. This link is yieldingly connected by a spring 23 to one end of a lever 24 pivoted at 25, the other end of the lever having a stud 26 cooperating with one of the stems of the motor bar 27. The other stem 10 of the motor bar is connected to one end of another lever 28 pivoted at 29 and connected to the lever 24. When the motor bar 27 is depressed, the link 22 is raised, through spring 23, and this causes the clutch and motor to give the machine a 15 stroke of operation.

As the motor operates the machine it rocks the main drive shaft 30 clockwise from the position of Fig. 1 and then allows the shaft to be returned counterclockwise under the influence of 20 springs, not shown. Fixed to the shaft 30 is an arm 31 connected by a link 32 to a full stroke sector 33. This full stroke sector carries a stud 34 adapted to engage the end of a projecting arm 35 on the link 22. As the motor gives the machine a stroke of operation the stud 34 engages the end of projection 35 and returns the link 22 downwardly to disengage the clutch so that the machine is given only a single stroke of operation. As the arm 31 on the main drive shaft 30 30 returns counterclockwise to normal, the full stroke sector returns upward and the stud 34 moves away from the end of the projection 35 on the link 22 so as to free the link but the link does not rise again, either because the motor bar 35 has not been held depressed or because, if it is held depressed, a latch mechanism 36, which is not necessary to describe in detail, holds the link down until the motor bar is depressed a second time.

40 Enforced designation feature

As heretofore mentioned, the enforced designation mechanism is associated with the motor drive so as to prevent operation of the machine unless certain designation keys or members are 45 manipulated, the designation keys in the present invention being illustrated in an intermediate bank of keys.

For this purpose a link 40 Fig. 1 is provided having a lateral lug 41 normally positioned over 50 a stud 42 on the link 22. The link 22 is thus normally prevented from rising to cause the motor to give the machine a stroke of operation.

The forward end of link 40 is connected to an arm 43 of a ball 44 pivoted on a shaft 45 supported on the framework of the machine. This ball is urged counterclockwise by a spring 46 against a limit stud 47. The ball is controlled by the enforced designation members, which, in this case, are a column of keys, as follows:

60 Referring to Fig. 3 which illustrates the column of enforced designation keys 50, it will be observed that, immediately under the stem of each key, is a pivoted bell crank 51 to which is connected the respective stop wire 52 for differentially positioning the actuator rack of the column of keys. The lower arms of these bell cranks extend through slots in a slide 53 on the key-board.

70 When one of the keys 50 is depressed, its bell crank 51 is rocked counterclockwise which moves the slide 53 rearward where it is latched by a latch 54 that engages in an opening in the slide (Figs. 2 and 3). It remains latched in this position until near the end of a cycle of operation of

the machine when all the latches 54 are automatically released by a releasing bail 55.

It is to be understood that the bank of enforced designation keys controls one of the racks 11 having an arm 12 carrying type bars 14 at its rear end so that, when one of the keys is depressed and the machine operated, the type bars of its bank are positioned so that a special or designating character may be printed at the time the machine is given a cycle of operation. 10

This bank of keys and its associated parts, thus far described, is similar to the other banks of keys and may be used for other purposes than enforced designation. In fact, one of the features of the present invention is that the bank of keys 15 that is used for enforced designation may also be used for other purposes. In the embodiment illustrated, the actuator rack for the bank of enforced designation keys, which is of slightly different form than the standard Burroughs 20 racks, controls the selection of the multiple registers by means of mechanism such as described in Patent No. 1,909,715. For this purpose, it is provided at its lower end with a link 56 corresponding to the link in said patent. It has not 25 been considered necessary to describe the details of this selecting mechanism in the present application.

When this bank of keys is conditioned for enforced designation purposes, as will be later described, it can be used not only to enforce a designation, but it can be used at the same time to select a particular register. When the bank is not being used for enforced designation purposes, it can still be used for the selection of registers, if 35 desired.

The slide 53 which, as above described, is moved rearward when a key is depressed, controls the enforced designation. This slide has a lug 60 at its forward end engaging under a projection 40 61 on an arm 62 pivoted at 63. This arm carries a stud 64 over which is hooked one end of a link 65 whose other end is connected to the bail 44 heretofore mentioned.

When one of the enforced designation keys 45 50 is depressed, its bell crank 51 is rocked counterclockwise which moves the slide 53 rearwardly. As the slide moves rearwardly, its lug 60 moves the arm 62 counterclockwise which raises the link 65 and rocks the bail 44 clockwise. This 50 pulls the link 40 from the position of Fig. 1 to that of Fig. 2 and frees the motor control link 22.

From the description thus given, it will be clear that the motor drive is normally blocked against 55 operation and that, unless one of the keys in the bank of enforced designation keys is depressed, the machine cannot operate even though the motor bar is depressed. In other words, if an operator enters an item in the machine but forgets 60 to depress an enforced designation key, the machine will not operate when he depresses the motor bar.

If it is desired to use more than one bank of 65 enforced designation keys suitable latches 62 and links 65 are provided for the chosen banks, in which event depression of a key in any of the enforced designation banks will release the machine.

Carriage control

70 Automatic means has been provided for controlling when the enforced designation feature shall be operative so that the machine may be used for calculations or operations with or without making it necessary for the operator to al- 75

ways depress an enforced designation key prior to operating the machine.

- The rear end of the link 40 which controls the movement of the motor control link 22 is pivoted 5 to an arm 70 fixed to a shaft 71 carried by the frame of the machine. This shaft has another arm 72 fixed to it which is yieldingly connected to a lever 73 pivoted at 74. This yielding connection is provided by having a pin 75 on the end 10 of arm 72 operate in a slot in link 76 carried on the end of lever 73. The stud 75 on the arm 72 is connected by a spring 77 to a stud on lever 73. The rear end of lever 73 is connected to an upwardly extending slide 80 having a pin and slot 15 connection 81 with a plate 82 carried by a stud 83 on the back plate 84 of the machine. The upper end of slide 80 has a stud 85 positioned in the path of a carriage tappet or cam 86 adjustably secured to the traveling paper carriage C. 20 When the paper carriage arrives in a columnar position where the enforced designation feature is not wanted, the cam or tappet 86 engages the stud 85 and moves slide 80 downward. This rocks the lever 73 clockwise and the latter, in turn, 25 rocks the arms 72—70 counterclockwise to push the link 40 from the position of Fig. 1 to that of Fig. 3 where it will be observed that the lateral lug 41 is out of the path of the stud 42 on the motor control link 22. 30 Accordingly, in predetermined columnar positions of the carriage the enforced designation feature is rendered inactive, or inoperative, or is disabled, and the machine may be used without it being necessary for the operator to depress enforced designation keys. 35

Modified form

- In the form of the invention heretofore described, the enforced designation feature is normally active and the carriage renders it inactive or disables it in predetermined columns. Another form of species of invention has been provided in which the enforced designation feature is normally inactive but the carriage renders it 45 active in predetermined columns. Associated with this form of the invention is a control of the enforced designation feature by several banks of keys in such a way that a key in each bank must be depressed before the machine can be operated. 50 Referring to Figs. 4 to 7, inclusive, a link 90 is provided similar to the link 40 heretofore described. This link has a lateral lug 91 adapted to be positioned in the path of stud 42 on the motor control link 22 but normally out of the 55 path of the stud as shown in Fig. 4. In the normal condition of the machine, therefore, it can be used for calculating purposes without requiring that the operator manipulate any enforced designation keys. The enforced designation mechanism is automatically rendered active under the control of the paper carriage as follows: 60

Referring again to Fig. 4, the rear end of the link 90 is provided with slots 92 in which operate studs 93 on the enlarged end of an arm 94, fixed 65 to the shaft 71. The rear stud 93 is connected by a spring 95 to an extension of the link 90 (Fig. 6) so that a yielding connection is provided between the arm 94 and the link 90. The shaft 71 carries another arm 72 yieldingly connected 70 to the lever 73 in the same manner as heretofore described for the construction of Fig. 1. Also, the lever 73 is connected to a slide 80 and the slide is operated in the same manner as heretofore described by a cam or tappet 86 on the 75 traveling paper carriage.

When the carriage arrives at a column where the enforced designation feature is desired, the cam 86, which has been properly positioned beforehand, moves the slide 80 downwardly, rocks the lever 73 clockwise and moves the arm 94 5 counterclockwise. The possible movement of arm 94 under these conditions is sufficient to move the link 90 from the position of Fig. 4 to that of Fig. 7, that is, to move the lug 91 from one side of the path of stud 42 to the opposite 10 side. Normally, however, the movement of the link 90 is blocked and the carriage moves the link only from the position of Fig. 4 to that of Fig. 6. The spring 95 yields under these circumstances to permit full movement of the arm 15 94.

In this way the enforced designation feature is automatically rendered active and the link 90 is put under tension for movement to the left (Fig. 6) when it is released by manipulation of 20 the designation keys as will now be described.

The forward end of link 90 is connected to an arm 100 of a bail 101 pivoted at 102. This bail is normally urged counterclockwise against a limit stud 103 by a spring 104. When the link 90 is moved forward by the paper carriage, as heretofore described, the bail 101 is rocked slightly clockwise, but it cannot move to its full extent because of certain latches 105 pivoted to the shaft 102. One of these latches has been provided in each of four banks of keys, as shown in Fig. 5. These latches are provided with shoulders 106 that are normally in the path of the edge of the bail and prevent full clockwise movement of said bail. Each latch is provided with a link 107 connected to a stud 108 on an arm 62 pivoted on shaft 63. These arms 62 are operated by slides 53 in the manner heretofore described. 30

When a key in a chosen bank of designation 40 keys is depressed, its slide 53 is moved rearwardly which rocks its arm 62 rearward and raises its link 107. This raises its latch 105 to released position. But the release of one of the latches 105 will not release the bail 101. Movement of 45 all the latches 105 to released position is necessary before the bail 101 can move. But, as soon as the last of the latches 105 is raised, the bail 101 moves clockwise under the influence of spring 95 to the position of Fig. 7 where, it will be observed, the motor control link 22 is released. 50

The number of banks in which latches 105 are provided can, of course, be varied, but whatever the number, it is necessary for a designation key to be depressed in each of the designation banks 55 before the machine can be operated.

To recapitulate on this species of the invention, the enforced designation feature is normally inactive. When the carriage reaches a predetermined column the enforced designation feature is rendered active and the machine cannot be operated unless one or more enforced designation keys are depressed. As soon as the required keys have been depressed, the machine is released for operation and will be operated upon depression of the motor bar. This species of the invention can, of course, be controlled by only one bank of keys, by providing a link 107, etc., in only one bank. 60

It is to be understood that the constructions shown are for the purpose of illustration only and that variations may be made in them without departing from the spirit and scope of the invention as defined by the appended claims. 70 75

I claim:

1. A machine of the class described having a traveling paper carriage, normally inactive blocking means preventing operation of the machine, means controlled by said paper carriage for moving said blocking means to active position and placing it under tension tending to move it out of active position, and a plurality of enforced designation devices controlling the final movement of said blocking means whereby when all said enforced designation devices have been manipulated said blocking means will move to release the machine.
2. A machine of the class described having a traveling paper carriage, normally inactive means for blocking operation of the machine, means controlled by the paper carriage for moving said blocking means to active position and placing it under tension, and a plurality of banks of enforced designation keys having connections for releasing said blocking means whereby when a key in each of said banks has been depressed said blocking means will be released for movement to release the machine for operation.
3. A machine of the class described having a calculating mechanism, paper supporting means, column printing control means for causing printing to occur in different columns on the paper supported by said supporting means, indexing means for indexing items in said machine, said indexing means and said machine being free at all times to enable said machine to receive items and to perform calculating functions, enforced designation means operable to require the manipulation of an enforced designation member concurrently with the conditioning of said machine for a calculation in order to release a predetermined machine part to enable said machine to be operated to perform said calculation, and means acting to automatically render said enforced designation means effective or ineffective in accordance with the column in which printing occurs to thereby force the designation of calculations printed in certain columns, but not of those printed in others.
4. A machine of the class described having a calculating mechanism, a traveling paper carriage movable from column to column across the machine, indexing means for indexing items in said machine, said indexing means and said machine being free in all columnar positions of the carriage to enable said machine to receive items and to perform calculating functions, an enforced designation means requiring the manipulation of an enforced designation member con-

currently with the conditioning of said machine for each type of calculation in order to release a predetermined machine part to enable said machine to be operated to perform said calculations, and means controlled by said paper carriage automatically rendering said enforced designation means effective in predetermined columnar positions of said carriage and ineffective in other columnar positions.

5. A machine of the class described having a calculating mechanism, indexing means for indexing items in said machine, a plurality of registers selectively movable to position for cooperation with said calculating mechanism, means for selecting said registers, paper supporting means, column printing control means for causing printing to occur in different columns on the paper supported by said supporting means, and means controlled automatically and selectively in accordance with the column in which printing occurs enforcing operation of said register selecting means concurrently with the indexing of an item in said machine in order to release a predetermined machine part to enable said machine to be operated to enter said item.

6. A machine of the class described having a calculating mechanism, indexing means for indexing items in said machine, a plurality of registers selectively movable to position for cooperation with said calculating mechanism, means for selecting said registers, a traveling paper carriage, and means controlled by said paper carriage acting automatically in predetermined columnar positions to force operation of said register selecting means concurrently with the indexing of an item in said machine in order to release a predetermined machine part to enable said machine to be operated to enter said item.

7. A machine of the class described having a calculating mechanism, indexing means for indexing items in said machine, a plurality of registers selectively movable to position for cooperation with said calculating mechanism, register selecting means controlled by a plurality of depressible keys, a blocking means normally in position to prevent operation of said machine, means operable by depression of one of said register selecting keys acting to move said blocking means to inactive position, a traveling paper carriage, and means controlled by said carriage acting to move said blocking means to inactive position in predetermined positions of said carriage to thereby make depression of said register selection keys unnecessary in said carriage positions.

ROBERT L. MULLER. 55
